CLIP FOR A MIRROR OR THE LIKE

Arthur Waller, Highland Park, Ill., assignor to Bull Dog Lock Company, Chicago, Ill., a corporation of Illinois

Application September 7, 1954, Serial No. 32,181

Term of patent 14 years

(Cl. D29—20)

FIG. 1

Figure 1 is a perspective view of a clip for a mirror or the like, showing my new design;

I claim:

The ornamental design for a clip for a mirror or the like, as shown.
